CLAIM

The ornamental design for a control unit for a solar tracker, as shown and described.

DESCRIPTION

The patent or application file contains at least one drawing executed in color. Copies of this patent or patent application publication with color drawing(s) will be provided by the Office upon request and payment of the necessary fee.

Figure 4.1: Front view of the control unit for a solar tracker;
Figure 4.2: Left view of the control unit for a solar tracker;
Figure 4.3: Rear view of the control unit for a solar tracker;
Figure 4.4: Right view of the control unit for a solar tracker;
Figure 4.5: Top plan view of the control unit for a solar tracker;

Figure 4.6: Bottom plan view of the control unit for a solar tracker;

Figure 4.7: Front perspective view of the control unit for a solar tracker;

Figure 4.8: Rear perspective view of the control unit for a solar tracker.

In the reproductions, the broken lines are for the purpose of illustrating portions of the control unit for a solar tracker that forms no part of the claimed design.
